ATTORNEY

UNITED STATES PATENT OFFICE.

CHRISTIAN HANSON, OF CHICAGO, ILLINOIS, ASSIGNOR TO ADVANCE PARCHOLITE CORPORATION, OF CHICAGO, ILLINOIS, A CORPORATION OF ILLINOIS.

CLUSTER CONSTRUCTION.

Application filed July 6, 1925. Serial No. 41,765.

This invention relates to a cluster construction and has for its primary object the construction of a cluster having many advantages over the cluster now in use.

5 An object of the invention is the novel inexpensive manner in which the parts are constructed and assembled.

Besides the above my invention is distinguished in the novel substantial manner 10 in which the balls are positioned and frictionally held in any adjusted position.

With these and other objects in view, the invention will be better understood from the following description taken in connection 15 with the accompanying drawings, in which:

Fig. 1 is a side elevation of a cluster constructed in accordance with my invention.

Fig. 2 is a top plan view with the cap removed and a portion in section.

20 Fig. 3 is a vertical sectional view.

Fig. 4 is a detail sectional view on the line 4—4 of Fig. 2.

Again referring to the drawing illustrating one of the many constructions of my invention the numeral 1 designates a shell which may be of any ornamental shape but shown in this particular instance as formed of two parts, a base 2 and cap 1^b frictionally engaging the base. The base 2 is formed 25 with a neck 3 that engages over the top of the lamp post 4 and is secured thereto by the nails 5. Thus it will be seen that in a very inexpensive manner the shell is formed and attached to the post. The base 2 is 30 further provided with openings 6 surrounded by a ring 7 pressed from the base.

Attention is called to the fact that the diameter of the opening 6 is slightly less than the diameter of the ball 8 so that the 35 wall of the opening will frictionally engage the ball to one side of its center. This ball 8 is provided with the usual neck 9 for attachment to the socket 10. A band 11 is secured to the interior of the shell in any suitable manner such as by spot welding and this band is provided with holes 12 of a diameter less than the ball so as to frictionally engage the ball to one side of its center and yieldably hold the ball in contact with

the wall of the opening. Attention is called 50 to the fact that the flattened portions 13 of the ball flatly engage flattened portions 14 and 15 of the holes and openings so that the balls may have the proper swinging movement but held against movement in a predetermined direction. This construction also 55 enables more effective grip between the balls and the band and shell.

It is, of course, to be understood that the shell may be constructed in various other 60 ways than illustrated and the ball yieldably engaged in various other ways and therefore I do not desire to be limited in any manner except as set forth in the claims hereunto appended.

Having thus described my invention, what I claim is:

1. In a cluster construction a shell consisting of a base having a neck and provided with a plurality of openings, a resilient band having spaced portions secured to the shell and provided with holes in alignment with said openings and balls frictionally engaged by the walls surrounding said holes and said openings.

2. In a lamp construction, a shell, a resilient band carried by the shell, said band and the shell being provided with aligned openings, and ball members confined between the band and the shell and held in close frictional contact with the surrounding walls of the openings by the inherent resiliency of the band, the ball members being adapted for reception of lamp sockets.

3. In a lamp construction, a shell, a resilient band within the shell and disposed in substantially concentric relation thereto, said band and the shell being provided with aligned openings, and ball members confined between the band and the shell and held in close frictional contact with the surrounding walls of the openings by the inherent resiliency of the band, the ball members being adapted for reception of lamp sockets.

In testimony whereof I affix my signature.

CHRISTIAN HANSON.
